UNITED STATES PATENT OFFICE.

JULIAN H. PITKIN, OF LAKE VIEW, AND JOHN F. STEWARD, OF CHICAGO, ILLINOIS; SAID PITKIN ASSIGNOR TO WILLIAM DEERING, OF CHICAGO, ILLINOIS.

SUPPORTING-FRAME FOR SELF-BINDING HARVESTERS.

SPECIFICATION forming part of Letters Patent No. 409,063, dated August 13, 1889.

Application filed April 12, 1888. Serial No. 270,503. (No model.)

To all whom it may concern:

Be it known that we, JULIAN H. PITKIN and JOHN F. STEWARD, citizens of the United States, residing, respectively, at Lake View and at Chicago, both in the county of Cook and State of Illinois, have invented certain new and useful Improvements in Frames for Self-Binding Harvesters, of which the following is a description, reference being had to the accompanying drawings.

The object of our invention is to reduce the weight and the cost of the frames of those harvesters which are used to carry and operate automatic grain-binding machines, and relates more particularly to those machines in which the harvester is provided at the stubble side with a single supporting and driving wheel, over which the cut grain is carried by a lifting mechanism to the binder, located outside of the wheel. As the binding mechanism may be in all its principal features of ordinary construction, we have represented in the drawings only such portions as are necessary to an understanding of our invention. We prefer to use the arrangement of gearing shown, described, and claimed in Letters Patent to Kennedy, Kennedy & Steward, No. 351,268, dated October 19, 1886, and we have therefore omitted from the drawings such portions of the same as are not directly associated with the matters claimed herein.

In the accompanying drawings, Figure 1 is a top plan view of our improved harvester-frame and certain portions of the binder-frame which are directly supported thereon, portions of the frames being broken away, as hereinafter described, to expose other parts to view. Fig. 2 is a rear elevation of the same. Fig. 3 is a stubble-side elevation. Fig. 4 is a sectional elevation on the line 4-4 of Fig. 1, showing a portion of the frame-work. Figs. 5 and 5^a are vertical sections on the lines 5-5 and 5^a-5^a, respectively, of Fig. 1, showing the connection of the finger-bar and the tongue support or pivot. Fig. 6 is a perspective view of one of the globular bearings in vertical section through its center. Fig. 7 is an outline view showing the rear elevation of a portion of the binder-frame and its support. Fig. 8 is a view of one of the blanks from which the main-frame clips are formed.

Fig. 9 is a perspective view showing the main shoe and guide for the knife-head. Fig. 10 is a perspective view of the harvester-frame and a portion of the binder-frame viewed from the rear stubble corner.

In a self-binding harvester of the type herein described it is necessary that the space provided for the passage of the grain from the platform to the binder shall be of such width fore and aft as to allow the long grain to flow thereto.

We construct the main-wheel frame of a width fore and aft only sufficient to admit the main wheel therein, and we construct our receiving-platform of correspondingly narrow width, while the elevating mechanism is constructed of greater width, as usual. In order that the weight of the elevator-frame may be properly supported on the "narrower main-wheel frame," as it is sometimes called, we extend the fore-and-aft sills of the wheel-frame forward of the cutter-bar, as usual, to support the front of the elevator and rearward beyond the rear sills of the platform to sustain the rear end of the elevator.

In the drawings the connected bars A and A' form the rear sill of the harvester-frame and the connected bars A² and A³ the front sill of the same. These front and rear sills are rigidly connected at the grain side by an angle-bar B, lying in a fore-and-aft direction and bolted or riveted firmly thereto. At the stubble side of the machine the front and rear sills are connected by two truss-frames lying in a fore-and-aft direction on opposite sides of the main-wheel space, as usual in machines of the present day.

The two trusses are substantially identical in construction, each consisting of a lower bar, chord, or sill, and of an upper bar, which is arched or raised at the middle. The truss on the grain side of the main wheel consists of the lower bar b, of L form in cross-section, applied to the under side of the front and rear sills A' and A³ and extended forward and rearward beyond them, and of the upper bar B², inclining downward from its middle to its two ends, which are seated above the sills A' and A³. The upper and lower members of the truss are united by intermediate clip-plates b⁵, which are passed partly around the

sills and riveted firmly to the upper and lower members of the truss, as plainly shown in the drawings.

The truss at the stubble side of the grain-wheel consists, as shown in Figs. 1, 2, and 3, of the bar or sill b^2 , applied below the sills and extended backward beyond the rear sill, and with the angular upper member B^3 connected thereto and to the main sills by the clip-plates b^5 in the same manner as in the inner truss. Between the inner truss and the grain-receiving platform we locate a bar B' , of angle-iron, extended in a fore-and-aft direction over the upper surfaces of and forward and rearward beyond the platform-sills A and A^2 , as shown in Figs. 1, 4, and 10.

From the foregoing it will be seen that the front and rear sills are firmly connected by the three bars b^2 , b , and B' , and that the last two bars project a considerable distance in advance of the front sill and a corresponding distance behind the rear sill.

The main-wheel frame comprises as its essential elements the two trusses and the sills A , A^2 , A' , A^3 . The essential members of the platform-frame are the bars B , B' and sills A , A^2 . The lower end of the bar b extends beyond the wheel-frame proper.

The elevator-frame is sustained, preferably, by two bent angle-irons C and C' , of the form shown in Figs. 1, 2, 3, and 10, located one at the front and the other at the rear, each iron consisting of a horizontal portion resting upon and bolted to the extended ends of the bars b and B' , an upright portion rising therefrom at the stubble side, and an upper horizontal portion turned grainward to receive and sustain the seat-plank D .

The elevator consists of horizontal rolls sustaining the upper and lower ends of endless carrier-aprons, as usual. We construct the side pieces C^2 and C^3 of the elevator-frame of sheet metal, bolting or riveting them to the supporting-arms C and C' , as shown in Figs. 1 and 2, the arms serving as their sole supports. The two sheet-metal pieces are given the requisite stiffness by means of wooden bars c^{10} , applied to their inner faces to support the journals of the elevator-rolls and the edges of the aprons, as in ordinary elevators. It will be observed that the front and rear sides of the elevator-frame are located one in advance of the cutter-bar, the other behind the rear sill A , A' of the main-wheel and platform frames, which frames have in a fore-and-aft direction a width much less than that of the elevator.

In order to support the wheel-frame adjustably upon the main wheel B^{12} , segmental racks-plates E' and E^2 are bolted to the inner sides of the respective trusses to receive pinions on the main-wheel axle, which will be provided with means for turning and locking it, as usual in this class of machines.

The grain-binder, which we prefer to construct of the ordinary Deering-Appleby type,

must be supported in the machine at the stubble side of the main wheel, so that it may be adjusted forward and backward, as usual, to secure the application of the band at the middle of the grain whether the latter be long or short. In order to afford proper support for the binder, which is constructed with a tubular base arm or support E^4 , lying in a fore-and-aft direction, we provide the segment-plate E^2 at the stubble side of the wheel with an arm or projection E^{12} rising from its upper end and forked or crotched, as shown in Figs. 1 and 3, to receive the base rod or arm E^4 of the binder, which is kept in place therein by a transverse pin e^9 . As an additional support for the binder, we bolt rigidly to the lower member b^2 of the stubble-truss an upright post E , the upper end of which is held by the brace b^4 , as shown in Fig. 3, this brace being formed by an upward and rearward continuation of the upper member B^3 of the truss. To the upper end of the post E we secure by a yoke-bolt, as shown in Figs. 2 and 3, the box or bearing E^3 , having externally a globular form, so that it may rock or tip to a limited extent in relation to its support. Through this globular box and through the tubular base-arm E^4 of the binder we pass the horizontal shaft E^{13} , provided at its forward end with cranks to carry the packers, as in the ordinary Appleby grain-binders. The shaft thus applied serves not only to drive the packers, as usual, but also as a partial support for the binder-frame, which is free to slide longitudinally thereon.

To prevent the parts from sagging or springing out of position the shaft is made of greater diameter than usual. At the rear end the shaft is grooved, and passed through and connected loosely by a groove therein and a longitudinal spline to a sprocket-wheel from which it receives motion, the hub of the wheel being provided, as shown in Fig. 3, with an annular flange f , which is seated in the upper part of a stationary oil-cup e , in the form of a flange, on the rear end of the bearing E^3 , this arrangement serving not only to apply oil to the shaft, but also to hold the wheel from moving sidewise as the shaft slides therethrough in adjusting the binder. As a further support for the binder when turned outward to its operative position, as in Fig. 7, we provide a bar G and bolt one of its ends to the rear upturned end b^3 of the member B^3 of the inner truss. From this point the bar is extended upward and stubbleward beyond the stubble side of the frame, and provided at its inner elevated end with a pulley G^2 , on which the customary arm G^3 of the binder-frame rests when in operative position. The bar G is sustained by two braces G' and G^4 , the former extending downward to the rear end of the truss member B^3 , and the latter extending rearward to the upturned end or brace b^4 . The precise arrangement of these supporting-braces is not material, and

may be modified within reasonable limits provided they give proper support to the bar G.

It will be observed that the binder receives support at three points: on the inner side from the arm E¹², the rear end of the packer-shaft, and on the outer side from the pulley G². These supports permit the binder-frame to be adjusted bodily forward and backward. They also permit the frame to be turned or folded inward toward the harvester around the packer-shaft as an axis. The folding of the binder upon the packer-shaft as an axis is not in itself claimed as a feature of the present invention.

H represents the usual crank-shaft of the harvester, extending in a fore-and-aft direction across the stubble side of the frame, provided at its forward end with the usual crank-wheel, and provided at the rear end with the usual driving-pinion and a sprocket-wheel for communicating motion to the other parts of the harvester in the customary manner. In order to permit this shaft to be located in the position shown and to secure certain bracing effects, we have adopted certain peculiarities in the construction of the truss at the stubble side. The rear end of the shaft passes through the tubular portion A' of the rear sill and through the clip b⁵ at the rear end of the truss. From this point the shaft rises slightly toward the front of the machine, where it is passed through and sustained by a box or bearing on top of the front sill A³, this arrangement throwing the crank-wheel farther from the ground than usual. The lower member or chord b² of the truss is in the same vertical plane as the shaft; but the upper member B³ of the truss is deflected grainward toward the forward end, so as to pass one side of the shaft. In order to permit this deflection the clip b⁵, which unites the upper and lower members of the truss at the forward end, is made from a blank in the form shown in Fig. 8. When this blank is doubled or bent, its upper and lower ends are thrown out of line or stand obliquely to each other in suitable positions to be riveted or bolted to the divergent members of the truss.

The tongue of the machine J' is connected to the frame by a horizontal pivot-bolt I', the ends of which are in turn encircled and sustained by metal straps b⁷ and b⁶, bolted, respectively, to the forward end of bar B' and the forward end of the lower member or chord b of the inner truss, as hereinafter explained in detail. In order to secure a greater breadth of tongue-bracing, or, in other words, to permit the use of a long pivot or attachment for the tongue, the inner truss—that is to say, the truss on the grain side of the main wheel—is deflected toward the stubble side as it approaches the front of the frame. This arrangement, which is plainly shown in Fig. 1, affords sufficient space between it and the outer truss for the admission of the main

wheel, but materially increases the distance between its forward end and the bar B'.

It will be perceived that the pivot of the tongue is located a considerable distance in advance of the forward sill A², so that when the machine is tilted forward the connections are subjected to great leverage and severe strain. We therefore strengthen the parts, as shown in Figs. 5 and 5^a. The front sill A², 75 which serves as the finger-bar, is of an L form in cross-section, with one flange extending downward. It terminates at the sill member b. A wrought-iron strap b⁶ is bolted to the under side of the member b, carried thence around the tongue-pivot I' and rearward beneath the depending flange of the finger-bar, and thence upward to the under side of the bar b, to which it is bolted at b¹⁰, thus forming, as shown, a truss to strengthen the forward extension of the bar b. The grain end of the tongue-pivot I', is encircled, as shown in Figs. 4 and 5^a, by a strap b⁷, applied to the horizontal flange of the bar B', and carried thence around the pivot and rearward under the bar 90 to the depending flange of the finger-bar, to which it is bolted, as shown at b⁸.

The inner or main shoe of the finger-bar is constructed in the manner represented more particularly in Figs. 1 and 9. It consists, 95 mainly, of a sheet-metal plate having its forward edge turned upward and then horizontally, as shown at c⁴, and its rear edge depressed and carried horizontally rearward beneath the horizontal flange of the finger-bar, 100 as shown in Figs. 5^a and 9, secured by rivets c', The end of the knife or sickle bar slides on this plate as a support, and is kept down to its place by two overlying plates c² and c³, which are riveted, respectively, to the horizontal flange of the finger-bar and to the horizontal top portion of the upturned edge c⁴ of the shoe. This light and simple shoe is found to answer all the purposes of the heavy cast-metal shoes formerly employed. A strap-bolt C³⁰, passing through the forward end of the truss member b, is riveted or otherwise attached to the metal bar C' and serves to hold the same firmly in place, this bar serving, as before explained, to sustain the forward end of the elevator-frame.

Heretofore binders have been usually supported upon the outer or stubble sill of the harvester-frame, and with a result that the parts are twisted or tipped out of position unless the binders were connected to the elevator-frame, commonly known as the "A frame." This attachment in turn rendered the construction of the A-frame objectionally heavy and rendered it necessary to strongly 120 brace their upper ends. Under our construction the binder is entirely disconnected from the elevator-frame, which latter may consequently be made much lighter than heretofore and supported at its lower end alone. 125

The tipping of the outward sill outward under the weight of the binder is in our ma-

chine largely prevented by the arm or strut G, which lies in such position that the weight of the binder acts upon the truss only in a downward direction. The bar or arm G also 5 serves to prevent the truss from tipping stubbleward.

In the drawings it will be observed that the bars B' and B² lie above the finger-bar with "distance-pieces" d¹² between them. 10 These distance-pieces are not essential, and may be omitted.

What we claim as our invention, and desire to secure by Letters Patent, is—

1. The harvester main-wheel frame having 15 the axle-guiding plate E², provided with the top arm E¹², and the standard E, erected on the rear stubble corner and provided with a box or bearing at the top in line with arm E¹², and forming the inner bearing of the binder, 20 whereby the frame is adapted to sustain a rocking or folding binder.

2. In a harvester and binder, the main-wheel frame having the axle-guiding plate E², with the top arm E¹², the standard E, 25 erected on the rear stubble corner and provided with a top box or bearing E³ for the packer-shaft, in line with arm E¹² and forming the inner bearing of the binder, and the rigid arm G, projecting stubbleward beyond 30 the remainder of the frame in position to sustain the outer side of the binder.

3. In a harvester main-wheel frame, the lower truss member b² and the standard E, secured to its rear end, in combination with 35 the upper truss member B³, having its rear end bent upward and secured to the standard, substantially as shown.

4. A harvester main-wheel frame having thereon on the stubble side a rigid arm E¹² 40 and a standard E, with a box or bearing E³ at its top, in combination with a grain-binding machine having the long tubular base-arm suited to turn and slide in the arm E¹² and the packer-shaft mounted in said base- 45 arm and extended beyond the same to slide through bearing E³, whereby the binder is permitted to rock inward and outward on the harvester, and also permitted to slide fore and aft thereon.

5. The binder-frame having the tubular base-arms E⁴ and G³ to sustain the packer-shaft and needle-shaft, respectively, in combination with the harvester main-wheel frame having the binder-frame mounted 55 thereon to turn about the axis of the packer-shaft as a center, said main-wheel frame provided with the rigid outreaching arm G, adapted to rest beneath the arm G³, whereby the binder is given direct support at its outer 60 side when in operative position.

6. In combination with the binder-frame having the long horizontal base-arm E⁴ enclosing the packer-shaft, the harvester main-wheel frame provided with a rigid arm or

standard wherein the arm E⁴ is mounted to 65 turn and to slide endwise.

7. The binder-frame provided with the rigid tubular horizontal base-arm E⁴, encircling the packer-shaft, whereby said arm is adapted to sustain the packer-shaft and also 70 to serve as a partial support for a sliding and turning binder.

8. In a grain-elevating harvester, a main frame to carry the main wheel and platform, provided with fore-and-aft bars B' and b, extended to overhang at the front and rear, in combination with the angular bars or frames C C', mounted on the overhanging ends of the bars B' and b, and the elevator side boards or frames C² and C³, secured to the 80 bars C C', substantially as described and shown.

9. In a main-wheel frame for a harvester and binder, the combination of its rear sill A', the bar b², located at the stubble side, attached to the sill, and extended rearward beyond the same, and a binder-supporting standard E, rigidly attached to the rear end of said bar b², whereby the binder is given support in rear of the sill. 90

10. The truss for a harvester main-wheel frame, consisting of a lower bar or member b² and an upper member b³, connected at its ends thereto, the upper member being arranged at one end directly over the lower 95 member, but deflected at the opposite end to one side of the lower member.

11. In a harvester main-wheel frame provided with the front support b⁷ for one end of the tongue-pivot, the truss at the grain side of the main wheel, extended at the front to sustain the support b⁶ of the tongue-pivot, said truss deflected stubbleward as it approaches the front of the frame, whereby the supports for the tongue-pivot are widely separated without impairing the strength of the frame or interfering with the wheel. 100

12. In a harvester-frame, the forwardly-extending bar b and the transverse sill or finger-bar A², in combination with the metal strap b⁶, secured to the under side of the bar and bent, as shown, to form a support for the tongue-pivot, and passed beneath the sill, substantially as described and shown, and secured at its rear end to the bar b, whereby it 115 is caused to act as a truss to hold the pivot in position.

13. In combination with the bar B' and the sill or finger-bar A² thereunder, the strap b⁷ to the upper face of the bar B', bent around the tongue-pivot and thence rearward on the under side to the lower edge of the sill and secured in place, substantially as shown. 120
